HOWARD MORSHEAD AND HARRY H. WIGGLESWORTH, OF PHILADELPHIA, PENNSYLVANIA, ASSIGNEES TO THE PHILADELPHIA DRYING MACHINERY COMPANY, OF PHILADELPHIA, PENNSYLVANIA, A CORPORATION OF PENNSYLVANIA.

DRYING MACHINE.

Application filed April 28, 1924. Serial No. 709,608.

This invention relates to drying machines, and is more particularly directed to machines of the type adapted for the drying of knitted fabric articles upon appropriately configured forms which are intermittently progressed through a drying enclosure, and successively presented exteriorly thereof for "stripping" and replacement with a fresh article to be dried.

10 More specifically, our invention has reference to a drying machine comprising an annular enclosure through which detached forms are progressed, in close radially disposed assembly, by means of an intermittently moved carrier, and associated means whereby said forms are relatively separated when exterior to the enclosure for stripping and reclothing.

15 An important object of this invention is to provide a compact drying machine of the above typified character, whereby considerable overhead and operating economy is effected, the output increased, and subsequent operations up to "boxing" of the dried articles incidentally expedited.

Other objects and attendant advantages inhering to our invention will be later on referred to, or become apparent from the following description of one practical embodiment thereof, as illustrated by the accompanying sheets of drawings constituting a part of this specification, wherein corresponding parts are designated by like indices in all the several views. It is desired, however, to state, at the outset, that our invention is not restricted to the details herein-after described, nor to the particular relative arrangement and aggroupment herein shown, except in so far as these may be specified by the subjoined claims.

In the drawings:

Fig. I, is a top plan view of a drying enclosure conventionally embodying our invention, with parts broken away and in section, to better disclose certain underlying elements.

Fig. II, is a vertical section of the same taken approximately on a plane indicated by the arrowed line II-II in the preceding view.

Fig. III, is an enlarged plan view of the mechanism for relatively separating the ar-

ticle-carrying forms when exterior to the drying enclosure.

Fig. IV is a sectional elevation of the same taken substantially on the line IV-IV in Fig. III.

Fig. V is a fragmentary plan view of a slightly modified form of the mechanism shown by Figures III and IV.

Fig. VI, is an elevation of the same.

Figs. VII, VIII and IX, are respectively a side, end, and plan views of the means whereby individual article-carrying forms are supported and guided into, and out of, the drying enclosure.

Before describing the specific devices constituting our invention, per se, it will be observed that the drying machine illustrated comprises a cylindrical enclosure, comprehensively designated by the numeral 10, provided with a roof 11 and diametrically opposed parallel vertical openings 12, 13 that afford ingress and egress for the series of article-carrying forms 14 hereinafter more specifically detailed. Within this enclosure 10, we support, in any conventional manner, upper and lower cylindrical conduits 15, 16, providing an interspace 17 through which the article-carrying form conveyor 18 projects and is revolved, as later on fully explained. It is well to note, at this juncture, that the co-ligned conduits 15, 16 are located in spaced relation from all angles with respect to the enclosure 10, thereby affording an annular drying space 19, and ample clearance for the free circulation of air with a looped directional flow—as indicated by the arrows in Fig. II.

Preferably, though not essentially, within the lower conduit 16, we locate a fan 20 which rotates in a horizontal plane, with the shaft 21 thereof journaled in a vertical bearing 22 supported within said conduit in any of the well known ways. Rotary motion is imparted to the fan 20 by means of a bevel gear 23, secured to the shaft 21, meshing with a complementary gear 24, on a radially disposed counter-shaft 25, provided with a pulley couple 26 for belt drive from any convenient line shaft—not shown. The counter-shaft 25 is also fitted with a worm drive 27, the purpose and function whereof will later on be fully set forth,

Concentrically located within the lower part of the enclosure 10 is an annular bank of pipes 28, through which heating medium is circulated in the well known manner; 5 supply and drip connections being fitted in connection therewith, but not shown as their location and function will be thoroughly understood by those acquainted with the art.

10 Referring, back again, to the form-carrying conveyor 18—which is pivotally mounted at the upper end of the vertical shaft 21—it will be remarked that it is substantially configured like unto an annular rack; that is to say, the rim 29, thereof, is of angular cross-section, and formed with a series of radially directed notches 30. The intervening lateral tooth-positions 31 of the angular rim 29 are reinforced by vertical webs 32, while 15 the entering edges of the notches 30 are rounded-off at 33,—as best shown in Fig. III—for a purpose hereafter explained. This conveyor 18, serves as a support and progressing instrumentality for the article-carrying forms 14, each of which is mounted upon a somewhat elliptically configured base or shoe 34, fitted with a depending and securely attached pin 35. These bases or shoes 34 are conveniently made of metal with the 20 pins 35 anchored therein during manufacture in any of the well known ways; and they are opposingly recessed to afford cavities 36 in which antifriction rollers 37 are journaled by means of countersunk studs 38, for example. Each base or shoe 34 is provided with an upwardly projecting flange 39,—Figs. VII-IX—and a hinged leaf member 40, between which the article-carrying form 14 is clamped by means of bolts 41 having 25 wing nuts 42. Thus it will be obvious that the forms 14 are removably mounted on the bases or shoes 34, with provision for expeditious change thereof, while it is further observable that each said form constitutes a 30 “detached” carrier.

To afford ingress and egress for the article-carrying forms 14, 14, into, and out of, the enclosure 10 aforesaid, we have provided the diametrically opposed—and parallel 35 spaced—openings 12, 13 hereinbefore referred to, which respectively permit entry and exit to associated tracks 43, serving in the capacity of opposed stations “a—a” whereat successive forms 14, 14, are presented to operatives for “stripping” and “boarding.” At this juncture, attention is directed to the fact that while we have illustrated an embodiment of our invention which may be aptly described as compound in character, 40 in that each station affords convenience for both operations of “stripping” and “boarding,” it is to be clearly understood that one such station “a” may serve for “boarding” and the other “a” for “stripping.” Furthermore, for small drying machines em-

bodying this invention, we may—with advantage—provide only one station “a,” as will be perfectly obvious to those acquainted with the art to which this invention appertains.

70

In the following description for the sake of brevity we will confine same to the details associated with one station “a” only, it being, of course, well understood, that the several parts incorporated in the opposed station 75 are merely a duplication thereof, technically arranged in reverse relation.

75

Each track or guide 43, it will be observed, comprises a pair of substantially U-shaped angle-sections affording co-planar horizontals 44, between which is a raceway 45 of a width to freely accommodate the depending pins 35 on the form supporting bases or shoes 34, and vertical guide rails 46. As best shown in Figs. III and IV, it will be noted that the outer vertical guide rail 46 terminates in abutment with the drying enclosure wall at 47, whereas the horizontal portion thereof is extended and beveled to provide a tongue 48 closely overlying the outer edge of the annular rack portion of the form-carrying conveyor 18. Similarly the inner vertical guide rail 46 terminates in close relation with the outer perimetrical edge of the form-carrying conveyor 18, while the horizontal portion thereof is extended and beveled to afford a tongue 49 snugly overlapping the lateral tooth portions 31 of the form-carrying conveyor 18. These opposed tongues 48, 49 are suitably configured in plan and by virtue of their beveled—or chamfered longitudinal—section, ensure free entry and exit for the bases or shoes 34, to the track or guide 43; it being quite obvious that the anti-friction rollers 37 thereunder will smoothly ride, onto and off, said tongues without disturbing the equilibrium of the form 14 supported thereby.

90

Cooperatively associated with the form-carrying conveyor 18 and track 43, we arrange intermittently actuated mechanism—now to be described—which is functional to transfer each successive article-carrying form 14 from the rotary conveyor 18 onto said track, and progress same by graduated stages thereover, subsequently returning said forms by similar movements back again to the conveyor 18 for passage through the drying enclosure 10, in closely associated radial relation. This intermittently actuated mechanism it is also to be particularly noted is likewise functional to move the form-carrying conveyor 18 with a step-by-step directional progress about the pivot 95 shaft 21 as hereafter fully explained.

95

Before proceeding further, it is well to remark that the track 43 is mounted upon vertical standards 50, Fig. II,—conveniently of standard angle section—braced by similar 100 section transverse ties 51 to ensure rigidity,

100

105

110

115

120

125

130

and for the purpose of affording support for certain instrumentalities now to be described.

Transversely of the drying machine, and 5 journaled in bearings 52, mounted upon one of the ties 51 aforesaid, is a drive shaft 53, having a worm wheel 54 secured thereon in mesh with the worm 27 hereinbefore referred to. This drive shaft 53, is, in turn, adapted 10 through a pinion and gear 55, 56 respectively to impart rotation to a counter-shaft 57, journaled in bearings 58, 58, mounted on a co-planal pair of the ties 51; and on said counter-shaft we spline a wiper arm 59 for 15 intermittent revolution of a vertical shaft 60 through co-action with a four-armed cam device 61 secured thereon. The vertical shaft 60 is journaled in a bearing 62 and it is provided with a radially-armed spider 63, functional to—in part—progress the article-carrying forms 14 over the tracks 43, as will be, hereafter, fully explained. In addition the vertical shaft 60 is also fitted with a star wheel 64, with which engages an anti-friction roller 65, pivotally mounted at the connection of a two part multiplying linkage 66, 67, the former or short portion—66—whereof is pivoted to an angle bracket 68 conveniently secured to the inner vertical 20 guide rail 46,—as best shown by Fig. III—whereas the longer member 67 is pivoted at 69 to a composite lever arm 70. This lever arm 70 is, in turn, fulcrumed to a vertical stub shaft 71 journaled in a bearing 72 secured on one of the aforesaid transverse ties 51, and it is fashioned with an obliquely directed lateral limb 73 having vertical lugs 74, 74 affording slidable support for a pawl 75, radially projected outwards relative to 25 the fulcrum 71 of said lever arm 70 under the action of a buffer spring 76 in the well known way. The one end (the upper with respect to Fig. III) of the composite lever arm 70 is fitted with an extension finger 77 pivoted thereto at 78, said finger being under 30 the action of a recoil spring 79. A heel 80 on the finger 77 limits movement thereof in one direction; or, normally holds said finger co-aligned with the lever arm 70. In somewhat similar manner the other end of the composite lever arm 70 is provided with a longitudinally movable plunger dog 81 under the action of a buffer spring 82 in accordance with conventional practice.

55 A contractile spring 83 connected at one end to a reinforcing rib 84 on the lever arm 70, and at its other end to a lug or eye-piece 85—Fig. I—provided for the purpose on the lower conduit section 16, serves to normally 60 retain said lever arm and associated linkage in the position shown by Fig. III.

In connection with the form-carrying conveyor 18, and to effectively safeguard against any possibility of back movement thereof, 65 we employ a gravity influenced pawl or dog

86 conveniently hinged for vertical swinging in a forked lug 87 on the inner guide rail 46, as clearly shown in Fig. III. This pawl or dog 86 is formed with an upset tooth 88 having a chamfered face, and it is automatically disengaged from the lateral tooth portions 31, of the form-carrying conveyor 18, immediately preceding cooperation therewith by the pawl 75, as later on more fully outlined.

Referring to Figs V and VI, we have illustrated a modified means for intermittently moving the lever arm 70, and for the sake of brevity, we will limit ourselves to an explanation of the novel features thereof, such other correlated elements shown—and having their counterpart in the foregoing detailed description—being correspondingly designated by like reference characters for the sake of establishing a proper association for the said novel features. Fundamentally, the distinction may be characterized as imparting motion to the stub shaft 71 positively, as against the employment of the multiplying linkage 66, 67. To this end, we extend the counter-shaft 57, and securely fix thereon a pair of diametrically opposed wipers 89, 90, for co-action with a cam device 91 rigidly attached to the extended lower end of the stub shaft 71, said device comprising opposingly functional lateral portions 92, 93, for a purpose later on explained; but, it may be here stated that said wipers and cam portions co-act to impart a lateral to-and-fro swinging movement to the lever arm 70, over a substantially ninety degree arcuate course.

Assuming the drying machine as illustrated is intended as a hosiery drier, and that the form-carrying conveyor 18 is progressed in a clockwise direction, it will be readily seen that when motion is imparted to the counter-shaft 25, the fan 20 and drive shaft 53 will be continuously revolved through the several gears hereinbefore described. Simultaneously, motion will be imparted to the counter-shafts 57 by the pinions 55 and gears 56. Each counter-shaft 57 will, in turn transmit an intermittent motion to the vertical shaft 60 by cooperation of the wipers 59 and cam devices 61, as hereinbefore explained. Now, referring more particularly to Figs. III and IV, it will be easily understood that the form-carrying base or shoe designated "b" has traversed the inclined tongue 49 and thereby been elevated from support by the conveyor 18 onto the track 43 with the depending pin 35 thereon entered into the raceway 45. Further, assuming that all the instrumentalities occupy—for the sake of ease in description—the respective locations illustrated, it will be apparent that as the vertical shaft 60 is intermittently rotated in a clockwise direction, the multiplying linkage 66, 67, will be projected and extended to

ward the left hand—in Fig. III—by cooperation of the roller 65 thereon with the approaching tooth of the star wheel 64. Simultaneous therewith the lever arm 70 will 5 be swung about its pivot 71, thereby advancing the form-carrying shoe 34 from the position designated “b” to an intermediate location designated “b” where it encounters an advancing arm of the spider 10 63, thence onward to that marked “c”, by initial co-action of the extension finger 77 with the depending pin 35. The movement of the lever arm 70 just described will be accompanied by transference of the 15 spring influenced pawl 75 over a lateral course of substantially ninety degrees while the dog 86 is forced downwards from the notch marked “x”, by the limb 73 engaging the chamfered face of the tooth 20 88, when pawl 75 will spring into said notch to effect progression of the conveyor 18 under recoil action of the spring 83. At the same time, it will be noted that as the shoe 34 approaches the position designated 25 “c” the pin 35 thereunder will have become engaged by one of the radial arms of the spider 63. The succeeding intermittent—or quarter-turn movement—imparted to the shaft 60 will progress the shoe 34 over the 30 track 43 to the position marked “d”, while the next succeeding quarter-turn of said shaft will effect traverse of said shoe to the location marked “e”. At this juncture it is well to note that an operative stationed 35 at the position “c”, and another at the station designated “e” can with ease and facility, respectively, perform the operations of “stripping” and “boarding” the forms 14.

Now, it is to be particularly observed that 40 the succeeding quarter-turn imparted to the shaft 60 will only transfer the shoe 34 from the position “e” to that designated “f” where it will remain until moved forwardly by the dog 81 into the enclosure 10. It is, also, to 45 be particularly noted that the pin 35 thereunder firstly moves the dog 81 inwardly in opposition to its buffer spring 82, on the return stroke of the lever arm 70 under the recoil of its spring 83, whereupon said dog 50 will be snapped at the rear thereof by expansion of the buffer spring 76. On the succeeding swing of the lever arm 70 to the right hand, it will be obvious that the linkage 66, 67 will again function as above set forth, whereupon the dog 81 will advance 55 the shoe 34 to the end of the raceway 45, where it will glide down the inclined tongues 48, 49 and be deposited on the conveyor 18, ready for progression through the 60 annular drying space 19 by means of the pawl 75, engaging each successive tooth 31, as hereinbefore set forth. At this point it is well to observe that each base or shoe 34 65 is shaped to provide an outer wall 94 conforming with the inner arcuate curvature

of the outer guide rail 46, and a reversely curved wall 95 of a radius to ride freely around the inner wall of the track 43, whereas the longitudinal dimension thereof is such to ensure easy radial disposition in the annular drying space 19 as indicated by the dot-and-dash line positions in Fig. III.

In the modified mechanism shown by Figs. V and VI it will be readily understood that, as the counter-shaft 57 rotates, the wiper 89 75 will traverse the cam arm 92 and impart a quarter-turn—for example—to the shaft 71 and armed lever 70 to the right hand as viewed in Fig. V. Incident to the right hand swing of the lever arm 70, the cam arm 93 is turned into the path of the wiper 90, which, as the shaft 57 continues to revolve, by engaging the arm 93, evolves a reversal of the lever arm 70. Further detailed explanation of this modification is deemed unnecessary, as anyone in the least acquainted with the art will clearly appreciate the positive to-and-fro swinging action imparted to the lever arm 70, by the wiper and cam device above described.

Obviously the progressive course of the several clothed forms 14 through the annular drying space 19 will be readily understood without further explanation, while it will be equally apparent that each consecutive form 14 is subjected to the movements above described at the stations designated “a”—“a”, intermediate egress and ingress with respect to the enclosure 10. However, it may be here remarked, that each form and associated shoe 34, is detached, and by virtue of the peculiar configuration given the said shoes we are enabled to compact the forms 14 in radially disposed close relation during progression through the drying space 19 105 whereby the capacity of the machine is greatly increased. Furthermore we desire to particularly stress the manner in which the successive forms 14 are separated from compact relation immediately upon entering the tracks 43 and positioned for “stripping”, thereafter traversing a semi-circitous course by co-equal stages; and returned into the drying enclosure by a two step increment travel. These features of the invention are deemed of prime importance, in that it affords proper spacing of the forms 14 whereby the operations above referred to, while closely associated, can be carried out efficiently. Incident to the compact radial assembly of the forms 14 while progressed through the space 19, it will be understood that the fresh hot air circulating upwardly through the cylindrical conduit 15, and downwardly through said annular space 19 will be—in a measure—choked about the article-carrying forms 14—where most essential—and thereby enhance the general efficiency of our machine, while the moisture-laden air drawn through the interspaces between the massed 110 115 120 125 130

shoes 34 is diffused with a relatively increased velocity against the banks of heating coils 28.

While the machine shown and described is of a compound character in that provision is made for two stations "a"—"a", whereat the dual operations of "stripping" and "re-clothing" the forms 14 are effected, it is to be explicitly understood that such disclosure 10 is by way of example only, as it is quite within the scope of our invention to provide a drying machine whereat the operation of "stripping" may be accomplished at one station "a" and the operation of "boarding" or 15 "re-clothing" the forms 14 effected at a diametrically opposed station "a". Still further it is our intention to construct small machines having only one station "a", whereat both operations of "stripping" and "boarding" 20 are effected. Furthermore attention is directed to the spring influenced extension finger 77 as accommodating return motion of the lever arm 70 when a form carrier base or shoe 34 is picked up by the advancing 25 arm of the spider 63 for movement to the "stripping" position—designated "c"; while the dwell period at the position "f" affords ample time for the operative to examine the reclothed form 14 prior to its projection in 30 to the drying space 19.

From the foregoing description and summary of the sequence of operations involved, it is thought that the numerous advantages and obvious efficiency of our improved drying machine will be thoroughly appreciated without further elaboration; and although we have somewhat minutely outlined one practical embodiment thereof, it is to be understood we are not limited thereby, further 35 than as indicated by the subjoined claims.

Having thus described our invention, we claim:

1. In a drying machine including an enclosure and means conveying forms therethrough in massed relation, coordinated means functional to withdraw and exteriorly separate consecutive forms, spacedly progress said forms, and return the same into the enclosure.

50 2. In a drying machine including an enclosure and means conveying detached forms therethrough in close radial relation, coordinated means functional to withdraw and exteriorly separate consecutive forms, spacedly progress said forms, and return the same by similar stages into the enclosure.

3. In a drying machine including an enclosure and means conveying forms therethrough in close radial relation, coordinated 55 means functional to withdraw and progress consecutively separated forms for stripping, and reclothing, and to return said forms by similar movements into the enclosure.

4. In a drying machine including an enclosure and means conveying forms there-

through in massed radial relation, coordinated means functional to withdraw and advance consecutively separated forms for stripping and reclothing, the withdrawing means also serving to return reclothed forms 70 into close assemblage within the enclosure.

5. In a drying machine including an enclosure and means conveying forms therethrough in massed radial relation, coordinated means functional to withdraw and advance consecutively separated forms for stripping and reclothing, the withdrawing means also serving to return the forms by similar stages into close radial relation 75 within the enclosure.

6. In a drying machine including a planetary conveyor and series of closely massed drying forms progressed thereby, means for withdrawing and advancing consecutive forms to widely separated relation, and 80 means operative during such advancement to intermittently progress the planetary conveyor.

7. In a drying machine including a planetary conveyor and series of article-carrying forms progressed thereby, means for concurrently withdrawing and advancing consecutive forms in separated relation and to intermittently progress the planetary conveyor. 85

8. In a drying machine including a planetary conveyor and series of article-carrying forms progressed thereby, means for withdrawing and advancing consecutive forms in separated relation, and means effective as 90 a result of such advancement to intermittently progress the planetary conveyor, the withdrawing means also functioning to return opposingly related forms into the drying machine. 100

9. In a drying machine including a planetary conveyor and series of article-carrying forms progressed thereby, means for withdrawing and advancing consecutive forms in separated relation, and means effective 110 as a result of such withdrawal to intermittently progress the planetary conveyor, the withdrawing means also functioning to consecutively return said forms into the drying machine with a dwell interval after reclothing. 115

10. In a drying machine including an enclosure and means conveying form carriers therethrough in close radial relation, means common to effect withdrawal of consecutive 120 forms to widely separated relation for stripping and to return the same after reclothing within the enclosure, and coordinated means effective to progress said forms by co-equal movements intermediate the stripping and clothing locations. 125

11. In a drying machine including an enclosure and means conveying form carriers therethrough in close radial relation, means common to effect withdrawal of consecutive 130

forms to widely separated relation for stripping and to return the same after reclothing within the enclosure, and coordinated means effective to progress said forms by co-equal 5 stages intermediate the stripping and clothing positions, said last mentioned progressive movements being comparatively less than the former.

12. In a drying machine including an enclosure and a planetary conveyor for progressing form carriers therethrough in close radial relation, the combination of a lever arm, a multiplying linkage for oscillating said arm, and intermittently actuated cam 15 mechanism for effecting withdrawal and return of the form carriers relative to the enclosure.

13. In a drying machine including an enclosure and a planetary conveyor for progressing form carriers therethrough in close radial relation, the combination of a lever arm, a multiplying linkage for oscillating said arm, and intermittently actuated cam mechanisms for effecting withdrawal and 25 turn of the form carriers relative to the enclosure, said lever arm having a spring influenced finger at the form withdrawing end and a plunger dog at the form returning end for the purposes specified.

14. In a drying machine including an enclosure and a radially notched planetary conveyor for progressing form carriers therethrough in close radial relation, the combination of a lever arm, a multiplying linkage 35 for oscillating said arm, intermittently actuated cam devices for effecting withdrawal and return of the form carriers relative to the enclosure, said lever arm having a spring influenced finger at its form withdrawing 40 end and a plunger dog at the form returning end, and an obliquely disposed spring influenced pawl carried by the lever arm for engaging in the radial notches aforesaid to intermittently progress the conveyor.

15. In a drying machine including an enclosure and a planetary conveyor for progressing detached form carriers therethrough in close radial relation, means functional to withdraw and progress consecutively separated forms for stripping and reclothing, and to return said forms by similar movements into the enclosure, said means affording a dwell period for successive reclothed forms in advance of their return into 55 the enclosure.

16. In a drying machine including an enclosure and a planetary conveyor for progressing detached form carriers therethrough in close radial relation, coordinated 60 means functional to withdraw and progress,

consecutively separated forms, and to return said forms by similar movements into the enclosure, means affording a dwell period for the reclothed forms in advance of their return into the enclosure, and means embracing a four armed cam device and cooperative wiper for intermittently actuating the coordinated means.

17. In a drying machine including an enclosure and means conveying detached form carriers therethrough in close radial relation, the combination of a form carrier comprising a base supported on anti-friction rollers and having reversely curved longitudinal walls to effect progressive guidance 75 exterior to the enclosure.

18. In a drying machine including an enclosure and means conveying detached form carriers therethrough in close radial relation, the combination of a form carrier comprising a base supported on anti-friction rollers and having reversely curved longitudinal walls to effect progressive guidance exterior 80 to the enclosure, and a radially armed intermittently moved spider for progressing said form carriers from stripping to reclothing location.

19. In a drying machine including an enclosure and means for progressing detached form carriers therethrough in close radial relation, the combination of an exteriorly located track for the form carriers of substantially U-shaped configuration affording 90 location for the operations of stripping and reclothing.

20. In a drying machine including an enclosure and means for progressing detached form carriers therethrough in close radial relation, the combination of an exteriorly located track for the form carriers of substantially U-shaped configuration affording location 100 for the operations of stripping and reclothing, said track having inclined entry and exit ends to effect transference of the form carriers from the progressing means, and vice versa, return thereto.

21. In a drying machine including a planetary conveyor and series of radially massed drying forms progressed thereby, opposed means for withdrawing and advancing successive forms in separated relation, and means operative during such advancement to intermittently progress the planetary conveyor.

In testimony whereof, we have hereunto signed our names at Philadelphia, Pennsylvania, this 23rd day of April, 1924.

HOWARD MORSHEAD.
HARRY H. WIGGLESWORTH
